Primary Examiner — Bridget L Eland*Assistant Examiner* — Lauren McVey(74) *Attorney, Agent, or Firm* — Oliff PLC(57) **CLAIM**

The ornamental design for a tape printing machine, as shown and described.

DESCRIPTION

FIG. 1 is a perspective view of a tape printing machine;
 FIG. 2 is a front view thereof, the rear view being a mirror
 image of the front view;
 FIG. 3 is a top view thereof;
 FIG. 4 is a left-side view thereof;
 FIG. 5 is a right-side view thereof; and,
 FIG. 6 is a bottom view thereof.

The broken lines depict environmental subject matter only
 and form no part of the claimed design.

1 Claim, 6 Drawing Sheets(56)
